CLAIM

I claim the ornamental design for a nightstand, as shown and described.

DESCRIPTION

FIG. 1 is a perspective view of my nightstand;

FIG. 2 is a front view thereof;

FIG. 3 is a left side view, the right side (not shown) is a mirror image thereof;

FIG. 4 is a top view of my nightstand;

FIG. 5 is a close up view of the area designated as area “5” in FIG. 2;

FIG. 6 is a close up view of the area designated as “6” in FIG. 2;

FIG. 7 is a close up view of the area designated as “7” in FIG. 5;

FIG. 8 is a close up view of the area designated as “8” in FIG. 2; and,

FIG. 9 is a close up view of the area designated as “9” in FIG. 8.

The broken lines are for environmental purposes only and form no part of the claimed design. The design features partially depicted inside of the circular center element of FIGS. 1 and 2 represent design features that are understood to be distributed uniformly within the circular center element in FIGS. 1 and 2.
